UNITED STATES PATENT OFFICE.

JOHN S. ADAMS, OF ELGIN, ILLINOIS.

WINDMILL STEERING MECHANISM.

SPECIFICATION forming part of Letters Patent No. 244,969, dated August 2, 1881.

Application filed November 24, 1880. (No Model.)

To all whom it may concern:

Be it known that I, JOHN S. ADAMS, a citizen of the United States, residing in Elgin, in the county of Kane and State of Illinois, have 5 invented a new and useful Windmill Steering Mechanism, of which the following is a specification.

My invention relates to improvements in geared or power windmills, in which, instead 10 of the tail-vane ordinarily used for steering purposes, there is substituted an automatic steering-wheel connected with the mast or fixed support of the turn-table by means of a speed-reducing train of gearing, which mechanism 15 not only steers and holds the windmill-head to the general direction of the wind, but also prevents the violent lateral oscillations to which a geared windmill steered by the ordinary tail-vane is subject in consequence of sudden fluctuations in the force or the direction 20 of the wind, or of sudden changes in the amount of power required by the machinery driven by the windmill; and the objects of my improvements are, first, to mount the steering-wheel 25 above the turn-table, in or near the prolongation of its vertical axis, by which arrangement to expose the steering-wheel to an unbroken wind-current and to relieve the turn-table gearing from excessive lateral strain; second, to 30 provide a reliable, durable, compact, and economical construction and arrangement of the parts supporting and operated by the steering-wheel; third, to provide means through which 35 the horizontal position of a windmill having its vertical axis within or upon a tubular mast or turn-table support may be automatically controlled with reference to the general direction of the wind by the action of a steering-wheel; fourth, to adapt a windmill, the wind 40 wheel of which is journaled in or upon an arm 45 of an independently-pivoted swinging-bracket, to be steered by and to operate in combination with an automatic steering-wheel and its connecting mechanism. I attain these objects by mechanism illustrated in the accompanying drawings, in which—

Figure 1 is a side elevation of a windmill embodying my invention, with the wind-wheel swung out of the wind. Fig. 2 is a longitudinal section through the box and the mast supporting the steering-wheel; and Fig. 3 is a side

elevation of a windmill embodying my invention, in which the mast of the steering-wheel is mounted directly over the vertical axis of the windmill.

55

Similar letters of reference indicate the same parts throughout the drawings.

A represents the tubular mast of the windmill, provided with flanges *a a*, by means of which it is secured to the cap of an ordinary 60 windmill-tower.

Passing through the mast A is a tubular turn-table, B, upon which is supported a swinging bracket, C, carrying the wind-wheel C'. The lower arm of the swinging bracket is 65 steered upon the turn-table at *c*, and its upper arm is provided with a pinion, *c'*, the hub of which is rigidly secured at its upper end to the swinging bracket, and its lower end is stepped, so that it may freely turn in the lower arm of 70 a bracket, D, rigidly secured to and moving with the turn-table.

The upper arm of the bracket D is provided with a stop or end bearing for the vertical shaft *d*, upon which shaft is secured a bevel-wheel, 75 *d'*, actuated by a similar wheel, *d''*, upon the hub of the wind-wheel C'.

E represents a reciprocating tube connected with and actuating a pitman, *e*, which is pivotally connected with the arm of a segment, *e'*, 80 journaled upon the rigid bracket D and gearing with the bevel-pinion *c'*, secured to and supporting the swinging bracket C upon the rigid bracket on the turn-table.

All of the parts above referred to have been 85 described and shown in detail, as well as claimed, in an application now pending in the United States Patent Office, and as they do not form an essential part of my present invention, only so far as they show one of its applications, no further description of them is necessary.

In the arrangement of parts shown in Figs. 1 and 2 the horizontal arms of the rigid bracket are perforated to receive a tubular mast, F, 95 which is rigidly secured to the bracket by set-screws *f* and *f'*, the latter of which also secures a collar, *f''*, upon the mast, to prevent vertical displacement of the sleeve L and the pinion *e''*. Mast F extends above the top of 100 the wind-wheel C' and terminates in a box or case G, provided with a cover, *g*, and with a

lateral extension, g' , forming a bearing for the horizontal shaft h of a steering-wheel, H , which shaft has upon its inner end and within the box a bevel-pinion, h' .

5 Within the tubular mast F is a vertical shaft, I , which extends some distance below the mast, and is provided upon its upper end with a loose sleeve, to which is rigidly secured the beveled wheel i and the pinion i' , as shown in Fig. 2. The pinion i' meshes with a gear-wheel, i^2 , sleeved upon a vertical stud, i^3 , which stud also carries the pinion i^4 , rigidly secured to gear-wheel i^2 and meshing with a gear-wheel, i^5 , rigidly secured to the vertical shaft I . The gear-wheel i^5 is provided with a hub, i^6 , revolving within an annular depression in the bottom of the box, which forms the vertical bearing and support for the shaft I , and also serves as a receptacle or reservoir for a lubricator for the bearing of the shaft. A collar, i^7 , rigidly secured to the top of the shaft I , prevents vertical displacement of the bevel-wheel i and the pinion i' .

By gearing the steering-wheel with the shaft I in the above-described manner it will be seen that while the steering-wheel may attain, during sudden violent changes of wind, a very high velocity, that of the shaft will be comparatively low, or, in other words, it is my intention to so proportion the train of gearing that it will require at least sixty revolutions of the steering-wheel to cause one revolution of the shaft, the purpose of which will be fully explained farther on.

35 In Fig. 3 is illustrated a different arrangement of the mast F and the train of gearing, which arrangement is in some respects preferable to that above described, and by which substantially the same results are secured.

40 The tubular mast F (shown in Fig. 3) is rigidly secured within a socket formed upon the top of the rigid bracket D , directly over the vertical axis of the windmill, and terminates in a gear box or case, G , much smaller than that shown in Figs. 1 and 2.

45 The bevel-pinion h' upon the horizontal shaft of the steering-wheel meshes with a bevel-gear, i , rigidly secured to the vertical shaft I' , and having a hub or annular flange, i^8 , which forms the vertical bearing and support for the shaft I' , substantially as previously described in relation to shaft I , Figs. 1 and 2. The lower bearing of shaft I' is formed in the upper arm of the rigid bracket D , through which it extends downward, touching, or nearly touching, the upper end of the vertical main shaft d , in which position it acts as a stop or end bearing to prevent the vertical displacement of the shaft d and its pinion d' .

50 Loosely sleeved upon shaft I' , below its bearing in the rigid bracket D , is a gear-wheel, i^9 , to which is rigidly secured a pinion, i^9 , which gear-wheel and pinion are vertically supported by the pinion i^9 , which is rigidly secured to the vertical shaft I' , and meshes with a gear-wheel, i^2 , loosely sleeved upon the vertical

shaft I . A pinion, i^3 , rigidly attached to and revolving with gear-wheel i^2 , meshes with gear-wheel i^4 upon shaft I' . The pinion i^5 , rigidly secured to and revolving with gear-wheel i^4 , meshes with gear-wheel i^6 , which is rigidly secured upon and communicates power and motion to shaft I , which shaft extends below the lower arm of the rigid bracket, in the same manner and for the same purpose as shaft I of Figs. 1 and 2.

55 Loosely sleeved upon shaft I , below and supporting gear-wheel i^2 and its pinion i^3 , is a sleeve, L , which forms a journal for pinion e^2 and the storm-vane M , which are rigidly secured upon it.

60 The lower end of shaft I (see Figs. 1 and 2) passes through and has its lower bearing in the housing K , rigidly secured to and revolving with the tubular turn-table, and is provided with a cap, k , above the housing, to exclude water, ice, &c., from its bearing. Housing K is provided with an annular flange, h' , journaled in a corresponding groove in the gear-wheel K' , which is rigidly secured upon the upper end of the tubular mast A , and meshes with a pinion, k^2 , rigidly secured upon the lower end of the vertical shaft I , so that when said shaft is revolved by the steering-wheel and its train of gearing the turn-table will be 95 revolved, carrying with it the rigid bracket and the mechanism secured thereto.

65 When the wind-wheel C' is out of the wind and at rest, as shown in Figs. 1 and 3, the face of the steering-wheel is parallel with the face of the wind-wheel; but when the wind-wheel is full to the wind the faces of the two wheels are at a right angle to each other. It will thus be seen that the normal position of the steering-wheel is edge to or out of the wind, 100 and consequently at rest during winds blowing steadily in one direction. In case of any material change in the direction of the wind the steering-wheel will be revolved by the action of the wind against one of its faces, and 105 will slowly revolve the turn-table upon its axis until the steering-wheel again stands edge to or out of the wind and ceases to move. In case of sudden changes in the direction of a severe wind the action of the speed-reducing train 110 of gearing will prevent violent lateral oscillation of the rigid bracket, and thus tend to prevent the violent contact of the wind-wheel and the rigid bracket which would result from the effects of such a wind upon a windmill when 115 steered by the ordinary tail-vane.

70 In my illustrations of the speed-reducing train of gearing I have shown only spur and bevel gearing; but I regard the use of a worm and worm-gear operating within the gear box 120 or case G as clearly within the scope of this invention.

75 The construction and action of the automatic governing mechanism of this windmill, consisting of the balance-vane N' upon one of the stop-arms, N , (see Fig. 3,) the storm-vane M and its connecting mechanism, acting in

combination with an ordinary tail-vane for steering purposes, having been described, shown, and claimed in the former application already referred to, it will only be necessary for me to show, describe, and claim them in their adaptation to operate in combination with my improved steering mechanism. To this end the pinion e^2 , which meshes with the segment e' and with the pinion c' , is rigidly secured to the sleeve L, revolving upon and independently of the mast F in Figs. 1 and 2, and the shaft I in Fig. 3. Sleeve L also carries a storm-vane, M, having an arm, m , rigidly secured by a set-screw, m' , to a collar, m^2 , which collar is rigidly secured to the sleeve L just above the pinion e^2 . Sleeve L is stepped in a cup-bearing, l, in the lower arm of the rigid bracket, and, as shown in Figs. 1 and 2, its upper end enters the upper arm of the rigid bracket, and has an end bearing against a collar, f^2 , upon the mast F.

When the wind-wheel is out of the wind the face of the storm-vane stands parallel to the wind-wheel, as shown in Figs. 1 and 3, and as the wind-wheel is swung into the wind the storm-vane swings into the wind in the opposite direction, so that when the wind-wheel is full to the wind their faces are again parallel, and the storm-vane extends slightly beyond the periphery of the wind-wheel. The area of the storm-vane is such that when an increasing wind attains the velocity required to produce a maximum strain upon the sails of the wind-wheel the wind-pressure upon the surface of the storm-vane will overcome the power of a counterpoise and cause the storm-vane and the wind-wheel to swing in opposite directions toward the rigid bracket and partially out of the wind, where they will be maintained at such an angle to an increasing wind as to maintain the wind-wheel from more than a maximum strain, and when running light, at a maximum velocity above referred to. In other words, my object is to avoid subjecting the wind-wheel to more than a desired maximum pressure of the wind, whether the mill be running heavy or light, as well as to prevent the wind-wheel from attaining more than a maximum velocity under any circumstances.

50 The combined action of the balance-vane and the storm-vane in an increasing wind tends to balance the force of the wind upon the wind-wheel and thus relieve the gearing of the turn-table from excessive strain. They also prevent injury to the wind-wheel or the mechanism of the windmill when struck by a sudden violent storm. The storm-vane acts instantly to swing the wind-wheel partially out of the wind, and the balance-vane acts to prevent violent contact of the stop-arm and the elastic cushion, and to return and maintain the wind-wheel at such an angle to the wind as to keep it in constant normal operation without risk of straining its parts or the machinery it operates.

65 The striking force of the wind-wheel against the rigid bracket, and the limit of its move-

ment away from the same, is relieved by means of the stop-arms N N, which engage with an elastic cushion, n, in the rigid bracket, which stops and cushion are particularly described and shown in my former application, as has also the means for manually operating the reciprocating tube E, the pitman e, and the segment e' .

By the combined operation of the steering mechanism, the balance-vane, and the storm-vane above described, the various movements of the wind-wheel are so nicely and automatically regulated that little or no care, except lubricating its parts, is necessary to keep it in perfect running order during the severest weather, and as it is effectually prevented from straining or injuring its parts its durability will far exceed that of any other windmill now in the market.

Although I have shown and described my improved steering mechanism as applied to a windmill having its wind-wheel journaled upon a vertically-pivoted swinging bracket, I wish it to be understood that I do not limit its application to that particular construction; for it is obvious that it may also be applied to windmills in which the wind-wheel is journaled in bearings rigidly secured to the turn-table or to the tail-vane bracket, or both.

What I claim, and desire to secure by Letters Patent, is—

1. In a windmill, the combination, with the wind-wheel, of a steering-wheel arranged above the same and adapted to swing the turn-table upon its axis, as and for the purpose described.

2. The combination hereinbefore set forth, with the wind-wheel and the turn-table, of a steering-wheel arranged above the wind-wheel, and a revolving shaft connecting said steering-wheel with and actuating the turn-table.

3. In a solid-wheel windmill, the combination hereinbefore set forth, with a wind-wheel and with a turn-table, of a steering-wheel and a storm-vane.

4. In a windmill, the combination, with a turn-table, and a wind-wheel pivotally connected with said turn-table, of a steering-wheel connected with and adapted to operate said turn-table, and a horizontally-swinging storm-vane independently pivoted in or upon the rigid bracket, as and for the purpose described.

5. The combination hereinbefore set forth, with the turn-table, the wind-wheel, the swinging bracket, and the steering-wheel, of a balance-vane, adapted to control the action of the wind-wheel, as and for the purpose described.

6. The combination, with the turn-table, the housing K, and the rigid bracket, of the mast F, box G, steering-wheel H, shaft I, and train of gearing connecting said shaft with the steering-wheel and the mast, substantially as described and shown.

7. The combination, with the swinging bracket, the turn-table, the rigid bracket, and the mast F, (or the shaft I,) of a storm-vane and pinion, e^2 , upon said mast, (or shaft,) and the

pinion c , supporting the swinging bracket, as and for the purpose set forth. 8. The combination, with the wind-wheel, the turn-table, the rigid bracket, and the storm-vane, of the sleeve L , journaled as described, and mechanism for connecting said sleeve with the wind-wheel, as and for the purpose set forth.

9. The combination, with the steering-wheel, the vertical shaft and mechanism connecting said shaft and wheel, of the turn-table, the housing K , the rigid gear-wheel K' , in which

the annular flange of the housing is journaled, and the pinion k^2 , rigidly secured upon the end of the vertical shaft, substantially as described and shown. 15

In testimony whereof I have hereunto affixed my signature this 19th day of October, 1880.

JOHN S. ADAMS.
